UNITED STATES PATENT OFFICE.

JEAN PIEL, OF SCHÖNEBERG, NEAR BERLIN, GERMANY, ASSIGNOR
TO AKTIENGESELLSCHAFT MIX & GENEST, TELEPHON- UND TELE-
GRAPHEN-WERKE, OF BERLIN, GERMANY.

PROTECTOR FOR TELEPHONE OR TELEGRAPH INSTRUMENTS.

SPECIFICATION forming part of Letters Patent No. 674,541, dated May 21, 1901.

Application filed November 2, 1900. Serial No. 35,285. (No model.)

To all whom it may concern:

Be it known that I, JEAN PIEL, a subject of the King of Prussia, Emperor of Germany, residing at Schöneberg, near Berlin, Kingdom 5 of Prussia, Germany, have invented a new and useful Improvement in Protectors for Telephone or Telegraph Instruments, (for which I have applied for a patent in Germany, which application was filed October 17, 1900,) of 10 which the following is a specification.

The electric-current protectors known as "heat-coils" or "sneak-current protectors" show the great inconvenience that when brought into action by sneak-currents they 15 interrupt the circuit, as they are supposed to do, but unfortunately leaving only a scarcely-visible mark of the performed action. Thus the great disadvantage arises, especially in telephone central offices, where an immense 20 number of similar protecting devices are crowded together, that the burning out of a heat-coil passes unnoticed until the operator's inability to reach a subscriber or the latter's complaint to the office reveals the fact.

25 In order to obviate the above-mentioned inconveniences, I avail myself of the well-known spring-controlling heat-coils, which when entering into action release a spring-blade or spring-controlled lever, in combination with 30 a mechanical contrivance provided with an electrical contact-making device, in such a way that any one of a certain number of said springs or levers belonging to one group will be enabled to set the said mechanical contrivance into motion, thus making an electrical contact that may actuate in the well-known manner an annunciator, a bell, or a register.

In the accompanying drawings, Figure 1 is 35 the end elevation, and Fig. 2 the top view, of a well-known multiple-carbon lightning-arrester with sneak-current protectors and the special alarm device that forms the object of the present application. Fig. 3 is a representation of the apparatus in connection with an 40 annunciator and a bell.

Fig. 4 shows a longitudinal section of the 45 heat-coil. It consists of a metallic spindle *q*, into which is soldered at *t* (with Wood's metal) a headpiece *p*. Around the spindle is wound 50 a coil *w* of insulated German-silver wire, the

ends of which are soldered to the spindle and to the cap *u*, respectively. The coil is surrounded by a metallic tube *h*, insulated from the rest by fiber pieces *v* and *v'*. This heat-coil is set between the rigid piece *k* and a 55 strong spring-blade *s*, the latter exerting a constant pulling force upon the headpiece *p*. A current entering at *k*, going over *u*, through *w*, over *t*, *p*, and *s* to the instrument will heat the coil *w* when above normal intensity and 60 gradually soften the solder until the spring-blade *s* will pull out the headpiece *p* of the spindle *q*, thus interrupting the circuit. On a base *b*, Figs. 1 and 2, a certain number of such heat-coils are set in rows, together with carbon 65 lightning-arresters, *c* and *c'* being carbon plates and *e e'* the ground-bar. A light swinging frame formed of an axis *x*, fulcrumed at *a* and *a'*, of the arms *f f'*, and the rod *r*, covered with an insulating-tube *y*, is slightly pressed 70 by a spring *m* against the row of spring-blades *s*. As soon as one of the spring-blades *s* is released, it will jump against the rod *r* of the swinging frame, overcome the spring *m*, and imparting an angular movement to the frame 75 bring the finger *d* of the latter into contact with the plate *g*, thus closing the local alarm-circuit, as shown in Fig. 3. The above-described contact device will constitute a useful subsidiary means for maintaining a central office in working order at a low expense, as for each group of fifty circuits only one contact device and one signaling device (drop, &c.) is required. It offers, moreover, the great advantage of allowing the inclosure of 80 the line-protectors in boxes, as the hitherto necessary and tiresome visual inspection of them is rendered superfluous, the annunciator indicating instantaneously the right box where the burning out takes place, it being 85 very easy for the attendant to locate the burned-out coil in that one box.

I am perfectly aware that heat-coils similar to the above-described have already been provided with contacts, one point being on the 95 spring *s* and the other just in front at a small distance from it, either on separated posts or on a common bar running throughout the whole length of a group. This has proved to be impractical for economical and technical 100

reasons, the use of individual contacts for each spring-blade necessitating an equivalent number of local circuits, a connection of them in multiple being not feasible on account of the resulting cross-connections between lines or instruments. On the other hand, the insulation of each contact-point from the spring and the use of a common bar as a second contact-point, which would allow their connection in multiple without cross-connecting the lines, would be prohibitive on account of the technical difficulties encountered and the immense expense.

I do not wish to limit the application of the above-described contact device to heat-coils only, but would expressly state that it may as well be used in connection with fuse-wires. Neither do I limit the application of the mechanical contrivance to electric-circuit closing, but would state that it also could be arranged to actuate a mechanical drop or annunciator.

What I claim as my invention, and desire to cover by Letters Patent, is—

1. The combination of a series of spring-controlling current-protectors, with a me-

chanical contrivance, independent from the current-protectors, appropriate to be moved to and fro, and arranged in the proximity of said series of current-protectors in such a manner, that it could be set in motion by any single one of said series of current-protectors, and means to produce a signal by the moving of said mechanical contrivance, substantially as and for the purpose set forth.

2. The combination of a series of spring-controlling current-protectors, with a swinging frame, adapted to be set in motion by any one of the springs of the said current-protectors, whenever any one of the latter enters into action, a contact-making device attached to said frame, an electrical circuit subject to be closed by said contact-making device and an annunciator inclosed in said circuit, substantially as and for the purpose set forth.

In testimony whereof I have signed my name to this specification in the presence of two subscribing witnesses.

JEAN PIEL.
